UNITED STATES PATENT OFFICE.

VICTOR W. NYE AND EDWARD M. AMTHOR, OF BUFFALO, NEW YORK.

AUTOMATIC TRAIN-STOPPING APPARATUS.

1,408,025.

Specification of Letters Patent. Patented Feb. 28, 1922.

Application filed October 23, 1919. Serial No. 332,660.

To all whom it may concern:

Be it known that we, VICTOR W. NYE and EDWARD M. AMTHOR, citizens of Canada and the United States, respectively, residing at 5 Buffalo, in the county of Erie and State of New York, have invented new and useful Improvements in Automatic Train-Stopping Apparatus, of which the following is a specification.

10 This invention relates to a train-stopping apparatus which automatically stops the train in case the engineer fails to heed the customary semaphore signals.

One of the objects of the invention is to 15 produce an apparatus of this character which will effectively apply the air brakes of the train and at the same time shut off the steam or other motive power of the engine.

20 A further object is to provide reliable electrically-controlled trip-mechanism operated by the usual semaphore arm controlled from the switch tower, in such a manner that said trip-mechanism is moved to its 25 operative position when the signal arm is extended to danger position.

A still further object is to provide improved automatic means for shutting off the motive power of the engine when the air 30 is released in the usual brake system for applying the brakes.

Another object is to produce an apparatus of this character which is simple in construction and efficient in operation and in 35 which the control devices carried by the engine are capable of installation on engines now in use and the trip mechanism is applicable to the customary semaphore arms without changing their construction.

40 In the accompanying drawings:

Figure 1 is a diagrammatic perspective view of the improved train-stop apparatus. Figure 2 is a side elevation of a steam locomotive equipped with the improvement. 45 Figure 3 is an enlarged sectional elevation of the control switches associated with the trip-mechanism. Figure 4 is a vertical section on line 4-4, Fig. 5. Figure 5 is a fragmentary sectional elevation of the trip 50 arm and associated parts. Figure 6 is a longitudinal section of the steam check valve. Figure 7 is a longitudinal section of a switch block showing a modified form of spring for normally closing the switch. 55 Figure 8 is a plan view of said spring.

Similar characters of reference indicate

corresponding parts throughout the several views.

In its general organization, this apparatus comprises a trip arm controlled electrically 60 by the danger signal or semaphore and adapted to project into the path of a tappet or arm on a locomotive to release the air of the brake system to automatically apply the brakes and shut off the motive power 65 of the engine, should the semaphore arm be in danger position and the engineer fail to observe the signal.

Referring more particularly to Fig. 1 of the drawings, 10 represents a portion of a 70 signal mast of the usual form, on the upper end of which is pivoted the signal or semaphore arm 11 of any well known type. This arm is controlled from the switch tower in the usual manner, and as shown in the drawings, is set in a horizontal position indicating danger. Mounted on the signal mast, preferably below the semaphore arm, is a vertically movable knife switch 12 operatively connected to the semaphore arm by 75 a link 13 pivoted at its opposite ends to the switch and semaphore arm. This switch is pivoted to the terminal posts 14 and is adapted to co-operate with upper and lower sets of terminals or contacts 15, 16, respectively. The knife switch 12 is controlled directly by the semaphore arm 11 and when the latter is in its horizontal or danger position, the switch-blades engage the upper set of contacts 15, while when the arm is in 80 its pendant or clear position, they engage the lower set of contacts in an obvious manner. The terminal posts 14 of the switch are included in a battery circuit 17, while the upper and lower sets of contacts 15, 16 are included in a motor circuit 18 which will 85 presently be described.

19 indicates a switch block or support on which are mounted two auxiliary switches 20, 21, preferably of the knife type, which 100 are included in the motor circuit and adapted to break or interrupt the same while the main control switch 12 is adapted to establish the circuit. The switch 20 is provided with front and rear terminals 22, 23, while the switch 21 is provided with front and rear terminals 24, 25, respectively. The arms of these switches are preferably mounted for vertically swinging movement on the block 19 and are normally held 105 closed by springs 26 fastened at their lower ends to the adjacent part of the support 110

ing member 27 of the switch block and at their upper ends to the operating levers 28 of the said switches. The latter are adapted to be opened at different intervals by 5 cam levers or trip arms 29, 30 carried by a rotary horizontal shaft 31 journaled in suitable bearings 32 and driven from a suitable motor 33 through a train of gears 34 or other suitable means. These cam levers are provided at their outer ends with rollers 30^a which are adapted to engage the undersides of the switch levers 28 to open the auxiliary switches at the proper moment. These cam levers are so positioned that they 10 are opened alternately. The gearing between the motor shaft 35 and the shaft 31 is reduced sufficiently to drive the last mentioned shaft at a comparatively slow speed.

Arranged adjacent the signal mast 10 and 20 loosely mounted on the shaft 31 is a trip device or arm 36 which in its operative position projects horizontally into the path of passing trains, as shown in Fig. 1, while in its inoperative position, it is inclined out 25 of the path of passing trains. This trip device is positively raised to its upper or inoperative position by a coupling device co-operating therewith and operated by the rotary shaft 31 when the semaphore arm is 30 moved to its clear position, while said trip device is adapted to be released from the coupling mechanism when the semaphore arm is moved to its danger position and to drop by gravity to its horizontal position, 35 as shown in Fig. 1. This coupling and releasing mechanism is preferably constructed as follows:

Keyed to the rotary shaft 31 is a trip wheel 37 having a tooth 38 which is adapted 40 to engage a pin 39 carried by the trip arm 36. This arm is free to slide laterally on its shaft but in its normal operative position its hub is adapted to bear against the hub of the trip wheel 37, in which position the 45 pin 39 is in the circumferential path of the tooth of said wheel, as shown in Fig. 5. When the shaft 31 is rotated, the tooth of the trip wheel 37 engages the pin 39 of the trip arm and raises the same to its inclined 50 inoperative position, as shown by dotted lines in Fig. 4, at which time the trip wheel is arrested owing to the motor 33 being stopped by the breaking of the circuit at the auxiliary switch 21. Arranged in the 55 path of movement of the trip arm and preferably vertically above the axis of the shaft 31 is a fixed cam 40 suitably secured to the adjacent bearing 32 of said shaft and having an inclined face 41, as clearly shown in 60 Figs. 1 and 5. The purpose of this cam is to withdraw the pin 39 carried by the trip arm from engagement with the tooth of the trip wheel 37 at a predetermined point in the movement of said arm. After reaching this 65 point, the trip arm is allowed to drop for-

wardly by gravity to its normal operative position, and during its downward movement is shifted laterally toward the trip wheel under the pressure of a spring 41 surrounding the shaft 31 and bearing at one 70 end against the hub of the trip arm and at its opposite end against a collar 42 fixed to said shaft. By this arrangement the pin of the trip arm constantly projects into the path of rotation of the trip wheel while the 75 trip arm is in its operative position. To limit the movement of the trip arm below its operative horizontal position, a suitable stop 43 is arranged on the adjacent part of the signal mast 10.

If desired, said trip arm may be provided with an extension 36^a adjustably carried by it to lengthen or shorten it to suit varying conditions. This adjustment may be effected by one or more set screws 36^b or other 85 suitable means.

When the semaphore arm is moved from the clear position to the horizontal danger position, shown in Fig. 1, the current flows from the positive pole of the battery 90 through a blade of the switch 12 to the corresponding upper terminal thereof and thence through the motor circuit 18 to the auxiliary switch 20 which is now closed. From the latter, the current flows through 95 the motor and completes the circuit back through the auxiliary switch and the main switch and thence to the negative pole of the battery. This closing of the circuit through the auxiliary switch 20 starts the 100 motor which in turn rotates the shaft 31 in a counter-clockwise direction through the train of gearing 34. The trip arm 36, which at the beginning of this operation was in 105 its upward or clear position, is carried further upwardly through the medium of the pin 39 and rotating trip wheel 37 against the inclined face 41 of the fixed cam 40 which deflects said trip arm laterally, disengaging its pin from the tooth of the trip wheel, 110 whereupon the trip arm drops by gravity to the operative position. The rotation of the shaft 31 continues until the cam lever 29 opens the corresponding switch 20, thereby breaking the circuit and stopping the 115 motor. When the semaphore is moved to its clear position, the main switch blades 12 engage the lower set of contacts, at which time the auxiliary switch 21 is closed and the switch 20 open owing to the conditions 120 previously described. The circuit is now closed through the auxiliary switch 21, operating the motor and rotating the shaft 31. During the rotation of the shaft, the trip wheel is rotated and carries the trip arm 36 125 upwardly to a predetermined point, at which time the cam lever 30 opens the auxiliary switch 21, breaking the circuit and stopping the motor. The trip arm is held in its inclined inoperative position by the engage- 130

ment of its pin with the tooth of the trip wheel 37.

It will be understood from the foregoing, that the main switch 12 controlled by the 5 semaphore arm is utilized for establishing the motor circuit, while the two auxiliary switches serve to break the motor circuit and thereby control the position of the trip arm 36.

10 The means located on the locomotive whereby the air brakes are automatically applied and the motive power shut off should the engineer fail to observe the danger signal, are preferably constructed as follows:

15 Referring more particularly to Fig. 2, 45 represents a locomotive of any well known type provided with the usual steam pipe 46, dry pipe 47, throttle stand pipe 48 and throttle valve casing 49 in which is located 20 the customary throttle valve. Interposed between the steam pipe 46 and the dry pipe 47 is a suitable emergency engine stop valve 50. Arranged in the casing 50^a of this valve is a check valve 51 which is adapted to 25 swing in the direction of the pressure of the steam passing therethrough. This valve is preferably in the form of a disk and is carried by a horizontal shaft 52 which extends through a stuffing box to the outside 30 of the valve. A bell crank lever 53 is attached at the outer end of this shaft for controlling the opening and closing of the check valve. When the engine is running, the valve is automatically held open by a locking 35 device which is preferably operated in conjunction with the air brake system of the train, said device being released to allow the check valve to close and shut off the supply of steam to the engine when the air brakes 40 are automatically applied in case the engineer fails to heed the semaphore signal. The preferred means for accomplishing this result comprise a cylinder or casing 54 which communicates with an air valve 55, 45 forming part of the air brake system, through the medium of a pipe 56. Arranged in this cylinder is a vertically movable piston 57 which is actuated by air pressure released from the brake system when said 50 valve is set for applying the brakes. The stem 58 of the piston projects above the top of the cylinder and carries at its upper end a detent or locking arm 59 which is normally adapted to engage a socket or depression 55 60 in the upper end of the vertical arm of the lever 53 and thereby hold the check valve open, as shown in Fig. 6. A spring 61 surrounding the stem of the piston and arranged between the top of the cylinder 60 and a collar 62 on said stem serves to normally keep the arm 59 in engagement with the lever 53. A weight 63 is provided on the horizontal arm of the lever 53 which causes the valve 51 to swing into the path 65 of the steam and be closed thereby, when

the arm 59 is released from said lever in a manner previously described. To reset the valve after the same has been closed, a bypass 64 is provided in the valve casing, which communicates with the inlet and outlet sides 70 of said valve, so as to equalize the pressure on both sides of the latter. This bypass is controlled by an equalizing valve 65, which is operated manually from the cab of the locomotive. As shown in the drawings, the 75 preferred means for actuating this valve comprise a hand wheel 66 secured to the rear end of a shaft 67 arranged longitudinally on the upper side of the locomotive, while its front end is provided with a bevel gear 68 meshing with a bevel gear 69 arranged on 80 the stem of the equalizer valve. When the pressure on both sides of the valve 51 is equalized, the valve is opened manually from the engine cab by a pull cord 70 fastened to 85 an arm 71 of the lever 53, thereby raising the lever and opening said valve. After the valve has been reset and held in its open position by the locking arm 59 engaging the bell crank lever 53, the equalizer valve is 90 closed.

The air valve 55, for effecting the application of the brakes of the train and for automatically shutting off the motive power of the locomotive, is opened by means of a horizontally arranged tappet 72 rigidly secured to the vertical stem 73 of the air valve and arranged in the path of the trip arm 36. The tappet, upon coming in contact with the fixed trip arm is tripped and turned rearwardly, 100 causing the air valve 55 to open. This opening of the air valve releases the air in the brake system, admitting air to the cylinder 54, raising the piston therein and releasing the detent from the valve controlling lever 105 and allowing the check valve to close. The air valve is returned to its normal position by a manually controlled lever 74 secured to its stem and located conveniently in the cab.

The operation of the device is as follows: 110

Assume the semaphore signal arm to be swung from its pendant or clear position to its horizontal or danger position, by the operator in the signal tower. The switch 12 controlled by the movement of the semaphore arm is simultaneously swung from the lower set of contacts 16 to the upper set of contacts 15, establishing the motor circuit 115 18 through the auxiliary switch 20 which at this time is closed, while the auxiliary 120 switch 21 is held open by the trip lever 30, the rotary shaft 31 having been stopped by the opening of said last mentioned switch during the movement of the semaphore arm to its clear position. In this position 125 of the semaphore signal, the trip arm 36 is held in its raised or inoperative position by the engagement of its pin 39 with the tooth 38 of the trip wheel 37. The instant the circuit is established by the switch 12, the cir- 130

cuit is closed through the auxiliary switch 20, whereupon the motor is started and the trip arm allowed to drop to its operative position, as hereinbefore described. By the continued rotation of the shaft 31, the trip lever 29 engages the operating lever 28 of the auxiliary switch 20 and opens the same, thereby breaking the motor circuit, stopping the motor and leaving the parts in the position shown in Fig. 1. As the oncoming train passes the signal block, the tappet 72 will be tripped rearwardly by the trip arm 36 arranged in the path of said tappet arm, opening the air valve 55 and applying the brakes. This opening of the air valve also actuates the piston 57, releasing the check valve lever, causing the check valve to close and shut off the steam from the engine pipe. Upon observing that the train has been automatically checked, the engineer closes the throttle. To restore the parts, the engineer closes the air valve 55 by means of the control lever 74 and then opens the steam control check valve 51 by first opening the equalizer valve 65, after which he resets the check valve by pulling the cord 70 to lock the same in its open position.

In Figs. 7 and 8 is shown a modified form of spring 75 used in connection with the auxiliary switches to hold them normally in their closed position. This spring is of the leaf type, one end of which is fixed to the switch platform 19, while the free end is provided with a longitudinal slot 76 which is adapted to engage the shank of a screw 77 carried by the operating lever 28.

While we have herein illustrated and described our invention in connection with a steam locomotive, it is to be understood that the controlling mechanism can be as readily applied to locomotives operated either by an internal combustion engine or by electrical power, without materially changing the arrangement and construction thereof.

We claim as our invention:

1. In an automatic train stopping apparatus, the combination with a locomotive having an accessory to be actuated, of a semaphore arm, an electric circuit, a motor in said circuit, a rotary member operated by said motor, a trip device arranged directly on said rotary member, a switch in said circuit controlled by the semaphore arm and co-operating with two sets of terminals included in said circuit, means in said circuit controlled by said rotary member for controlling the movements of said trip device, and means on the locomotive arranged to be tripped by said trip device for actuating said accessory.

2. In an automatic train-stopping apparatus, the combination with a locomotive having an accessory to be actuated, of a semaphore arm, an electric circuit, a motor in said

circuit, a rotary member operated by said motor, a trip device arranged on said rotary member, a main switch in said circuit controlled by the semaphore arm and co-operating with two sets of terminals included in said circuit, a pair of auxiliary switches connected with said sets of terminals, respectively, means on said rotary member operating said auxiliary switches to control the position of said trip device, and means on the locomotive arranged to be tripped by said trip device for actuating said accessory.

3. In an automatic train-stopping apparatus, the combination with a locomotive having an accessory to be actuated, of a semaphore arm, an electric circuit, a motor in said circuit, a shaft rotatable by said motor, a trip device loosely arranged on said shaft, means on said shaft for positively raising said trip device, a main switch for establishing the motor circuit controlled by said semaphore arm and co-operating with two sets of terminals included in said circuit, a pair of auxiliary switches included in said circuit, means on said rotary shaft for opening said last-mentioned switches to break the circuit to control the position of said trip device, and means on the locomotive arranged to be tripped by the trip device for actuating said accessory.

4. In an automatic train-stopping apparatus, the combination with a locomotive having an accessory to be actuated, of a semaphore arm, an electric circuit, a motor in said circuit, a shaft rotatable by said motor, a trip device mounted on said shaft, a main switch for establishing the motor circuit controlled by said semaphore arm, a pair of auxiliary switches included in said circuit and normally closed, cam levers carried by the rotary shaft and adapted to open said auxiliary switches, means operated by said shaft during a portion of its revolution for raising said trip device to its inoperative position, means for returning said trip device to its operative position during the remaining portion of the revolution of said shaft, and means on the locomotive arranged to be tripped by the trip device for actuating said accessory.

5. In an automatic train-stopping apparatus, the combination with a locomotive having an accessory to be actuated, of a semaphore arm, an electric circuit, a motor in said circuit, a shaft rotatable by said motor, a main switch for establishing the motor circuit controlled by said semaphore arm, a pair of auxiliary normally-closed switches included in said circuit, cam levers carried by the rotary shaft for opening said auxiliary switches at different times during the revolution of said shaft, a trip device loosely mounted on said shaft, a coupling device rigidly mounted on the latter and co-operating the trip device to raise the

same during a portion of the revolution of said shaft, means for returning said trip device to its operative position during the remaining portion of the revolution of said shaft, and means on the locomotive arranged to be tripped by the trip device for actuating said accessory.

6. In an automatic train-stopping apparatus, the combination with a locomotive having an accessory to be actuated, of a semaphore arm, an electric circuit, a motor in said circuit, a shaft rotatable by the motor, a trip device loosely mounted on said shaft, a main switch for establishing the motor circuit controlled by said semaphore arm, a pair of auxiliary normally-closed switches included in said circuit, cam levers carried by the rotary shaft and adapted to open said auxiliary switches at different intervals during the revolution of said shaft, a coupling device mounted on the latter and co-operating with the trip device to raise the same, a cam for disengaging the trip device from said coupling device when the semaphore signal is moved to danger position, and means on the locomotive arranged to be tripped by the trip device for actuating said accessory.

7. In an automatic train-stopping apparatus, the combination with a locomotive having an accessory to be actuated, of a semaphore arm, an electric circuit, a motor in said circuit, a shaft rotatable by said motor, a trip device arranged on said shaft, a main switch for establishing the motor circuit controlled by said semaphore arm, a pair of auxiliary switches included in said circuit, means on the rotary shaft for opening said auxiliary switches at different intervals during the revolution of said shaft, means for moving the trip device into and out of operative position, and means on the locomotive arranged to be tripped by the trip device for actuating said accessory.

8. In an automatic train-stopping apparatus, the combination with a locomotive having an accessory to be actuated, of a semaphore arm, an electric circuit, a motor in said circuit, a main switch for establishing the motor circuit controlled by the semaphore arm, a trip device, means controlled by said motor for moving said trip device into and out of operative position, a pair

of auxiliary normally-closed switches included in said circuit, means controlled by said motor for opening said switches, and means on the locomotive arranged to be tripped by the trip device for actuating said accessory.

9. In an automatic train-stopping apparatus, the combination with a locomotive having an accessory to be actuated, of a semaphore arm, an electric circuit, a motor in said circuit, a shaft rotatable by said motor, a main switch for establishing the motor circuit controlled by said semaphore arm, a pair of auxiliary normally-closed switches included in said circuit, cam levers carried by the rotary shaft for opening said auxiliary switches at different times during the revolution of said shaft, a trip device loosely mounted on said shaft, a trip wheel rotatable with said shaft and having a tooth for engaging said trip device to elevate the same, and means on the locomotive arranged to be tripped by the trip device for actuating said accessory.

10. In an automatic train-stopping apparatus, the combination with a locomotive having an accessory to be actuated, of a semaphore arm, an electric circuit, a motor in said circuit, a shaft rotatable by said motor, a main switch for establishing the motor circuit controlled by said semaphore arm, a pair of auxiliary normally-closed switches included in said circuit, cam levers carried by the rotary shaft for opening said auxiliary switches at different times during the revolution of said shaft, a trip device loosely mounted on said shaft and laterally movable thereon, a trip wheel rotatable with said shaft and having a tooth, said trip device having a projection arranged to be encountered by said tooth to elevate the device, a cam for shifting the projection of the trip device out of engagement with said trip wheel when the trip device is elevated to a predetermined point, and a spring for shifting the trip device toward said trip wheel, and means on the locomotive arranged to be tripped by the trip device for actuating said accessory.

VICTOR W. NYE.
